CLAIM

The ornamental design for a doll or similar article, as shown and described.

DESCRIPTION

FIG. 1 is a top plan view of a doll or similar article
showing my new design;
FIG. 2 is a front elevational view of the doll;
FIG. 3 is a side elevational view of the left side of the doll, an elevational view from the right side of the doll would be a mirror image of the FIG. 3;
FIG. 4 is a rear elevational view of the doll; and,
FIG. 5 is a bottom plan view thereof.

FIG. 1

FIG. 3

FIG. 5
